United States Patent Office

Des. 189,246
Patented Nov. 15, 1960

189,246

TABLE

Albert William Beck, 12528 Woodside Drive,
Saratoga, Calif.

Filed Apr. 13, 1959, Ser. No. 55,470

Term of patent 14 years

(Cl. D33—14)

Fig. 2.

Fig. 5.

Fig. 4.

I claim:

The ornamental design for a table, substantially as shown and described.
